UNITED STATES PATENT OFFICE.

FRED E. DAVIS, OF FREEPORT, ILLINOIS, ASSIGNOR TO PERFECTION VAPOR LIGHT CO.,
A CORPORATION OF ILLINOIS.

LAMP.

1,231,716.

Specification of Letters Patent.

Patented July 3, 1917.

Application filed January 19, 1914, Serial No. 813,026. Renewed May 19, 1917. Serial No. 169,777.

To all whom it may concern:

Be it known that I, FRED E. DAVIS, a citizen of the United States, and a resident of Freeport, county of Stephenson, and State of Illinois, have invented certain new and useful Improvements in Lamps, of which I do declare the following to be a full, clear, and exact description, reference being had to the accompanying drawings, forming 10 part of this specification.

The invention relates to vapor lamps, and seeks to provide a lamp having efficient means for vaporizing gasoline, kerosene or the like, mixing the vapor with air and 15 burning the mixture to heat a mantle to incandescence. The invention consists in the features of improvement hereinafter set forth, illustrated in the preferred form in the accompanying drawings, and more particularly pointed out in the appended 20 claims.

In the drawings, Figure 1 is a side elevation of the lamp with the shade and tank shown in section. Fig. 2 is a plan view of 25 the deflector plate. Fig. 2^a is a detail view illustrating two burners which can be substituted for the single burner. Fig. 3 is a sectional view of the gas generator and single burner. Fig. 4 is a sectional view 30 of the valve casing and adjacent parts. Fig. 5 is a sectional view on the line 5—5 of Fig. 4. Fig. 6 is a sectional view of the generating cup. Fig. 7 is a sectional view of a tip-cleaning appliance. Fig. 8 is 35 a section on the line 8—8 of Fig. 3.

The improved device comprises a base having an outer shell 1, an inner shell 2 and a convex bottom 3 having a down-turned flange 3' soldered or otherwise suitably secured to the lower edge of the shell 2 to form a tight joint therewith. The shell 2 and the bottom 3 form an air and liquid tight tank in which the gasoline or kerosene is to be contained. The inner and outer 45 shells 1 and 2 are preferably dome-shaped, as shown and fit one within the other, and the inner shell may be made of any cheap material and stamped to form. The outer shell, however, should be well made and 50 nickel plated or otherwise finished to give it a pleasing appearance. These shells when in place are approximately in contact with each other at the top but their lower edges slope outwardly, that of the outer shell somewhat more than that of the inner, 55

leaving a space between them. A strip of felt 4 is placed around the outside of the lower edge or flange of the inner shell and extends slightly below said flange. The outer shell is then pressed down and as the 60 space between the shells narrows, the felt is clenched and, when the shells are in position, (see Fig. 1) is securely held, thus forming a soft cushioned edge to contact with the surface upon which the lamp is 65 placed. A hole is formed through the top of both shells and a tube 5 is rigidly secured to a flange 6 on the inner shell 2. This tube 5 extends down into the tank about half way to the bottom and upwardly a 70 short distance. Its upper end is externally threaded, as shown in Fig. 4, and a valve casing 7 is screwed onto this threaded portion. An outwardly projecting flange 8 on the lower end of the valve casing 75 engages the upper surface of the shell 1 and clamps it in position with the felt strip 4 clenched between the lower outer edges of the shells, as above described.

A cylindrical chamber 7' is formed in 80 the lower portion of the valve casing 7 and extends upwardly therein a short distance above the inner end of the tube 5 (see Fig. 5). The lower end of a short, upwardly curved pipe 9 is screwed into the side of 85 the valve casing and communicates with the chamber 7 thereof. A cap 10 (see Fig. 5) is threaded upon the upper end of the pipe 9 and a washer 11 in the cap 10 engages the end of the pipe 9 to prevent leakage. 90 The cap has a portion 12 extending down into the pipe and an upwardly projecting, internally threaded flange 13. The portion 12 has a bore terminating in a restricted port 14 and a valve 15, loosely fitting the 95 bore, is arranged to close this port. A nipple 16 threaded into the flange 13 of the cap has a bore terminating in a restricted port 17 which is smaller than the valve 15. The latter is provided with conical ends 100 that extend within and close the restricted ports 14 and 17. A short stem 18 connected to the valve extends through the port 16 and is provided with a perforated disk 19 upon its outer end. The outer end 105 of the bore of the nipple is shaped to engage a small air pump. The cap 10 may be readily removed when it is desired to pour liquid fuel into the tank. The flow into the tank is, of course, checked as soon as 110

the level of the liquid reaches the lower end of the pipe 5, so that space is provided in the tank for air under pressure. When it is desired to supply compressed air to the tank, it is only necessary to unscrew the nipple 16 until its shoulder 20 engages the disk 19 and raises the valve 15 and air can then be forced through the cap and into the tank with a small pump. During the pumping operation, the valve 15 acts as a check valve to prevent back flow from the tank. After the desired pressure is obtained, the cap is screwed down and the valve 15 is securely held in position and prevents any leakage through the port 14.

From the upper end of the cylindrical chamber 7' of the valve casing 7 extends a short, vertical channel 22, into the lower portion of which is screwed a small supply pipe or tube 23, that extends down through the pipe 5 and into the tank almost to its bottom. The arrangement of the supply pipe 23 and the filler pipes 5 and 9 avoid the necessity of forming more than one opening in the fuel tank.

The upper end of the channel 22 communicates with a small channel 24 which extends at right angles thereto into the bore of a projecting boss 25. A needle valve 26, threaded through the bore of the boss 25, engages a valve seat 27 at the outer end of the channel 24 and controls the flow of liquid fuel therethrough. A small channel 32 extends from the seat of the valve 27 to a cylindrical chamber 33 in the upper portion of the valve casing 7. A pipe 34 having a flange 35 is screwed into the end of the chamber 33 and a washer 36 pressed between the flange 35 and the upper end of the valve casing 7 forms a tight joint between the pipe 34 and said casing.

A small shaft or rod 37 extends outwardly through an outwardly extending portion 38 on the casing 7 and the cap 39 having its end filled with packing 40 is screwed on to the extended portion 38 to insure a tight joint, while the outer end of the rod is bent to form a crank arm 41 in order that the rod may be readily turned. The inner end of this rod or shaft is threaded into a disk 42 which is preferably hemispherical in shape and engages one side of the cylindrical chamber 33. A pin 43 eccentrically disposed on the flat face of the disk 42 loosely engages a hole in the flattened lower end 44 of a rod 45. The lower end of the rod is arranged between the disk 42 and a T-shaped piece 46 which is fixed to the bottom wall of the chamber 33, and maintains the rod in engagement with the crank pin 43. The rod 45 is small and somewhat flexible and its upper end is adjustably threaded into the lower end of a larger filler rod 47. A lock nut 48 is threaded on the rod 45 and engages the lower end of the

filler rod 47. The latter fits loosely within the tube 34, and its upper end is tapered and is provided with a bore in which a fine tube 49 is secured. A fine wire 50 is inserted in the upper end of the tube 49 and is held therein by pinching or compressing the end portion of the metal tube 49 to securely grip the wire, as shown in Fig. 7. The upper end of the rod 47 is also compressed to grip and secure the tube in place. In this manner, the fine wire tip cleaner which is formed of tempered steel and has a diameter of about five thousandths of an inch, is cheaply and securely fastened to the upper end of the rod 47.

The upper end of the tube 34 extends above the filler rod and is provided with a tip 51 which is threaded into the tube and extends a short distance above its upper end. The channel or bore 52 of this tip 51 has a contracted, conical upper end that communicates with a fine opening or discharge port 53 of a composition tip piece 54. The upper end of the tip 51 is bored out to form a recess for the tip piece 54 and the walls 90 of this recess are preferably undercut to form an inwardly inclined or contracted annular flange 55. The composition tip piece 54 is molded with this recess and is preferably formed by mixing two parts by weight 95 of Portland cement and one part of plaster of Paris with a saturated solution of salt, and filling the tip recess with this mixture. Before the composition sets, the fine wire 50 is extended through it. After the composition has hardened, the wire is withdrawn and, in this way, a fine smooth hole or discharge port is cheaply and accurately formed in the tip piece, through which the vaporized fuel is ejected into the mixing 105 passage. In similar all metal tips, it is difficult and expensive to drill such ports which must have a very small diameter, must be accurately formed and free from burs in order to accurately direct the stream of vapor into the opening of the mixing passage. In the present tip having a composition tip piece molded in place about a fine wire as a core, the fine opening or port is accurately and economically formed. The particular 110 composition set forth very soon sets after being placed in the tip and when the lamp is used, it quickly vitrifies and hardens.

The upper portion of the tip 51 is threaded into a central opening of a disk 56 120 which is formed at the lower portion of an inverted U-shaped mixing chamber or passage 57. The central portion of this curved passage has an inlet port 58 on its underside surrounded by a flange 59. The port 125 58 is in axial alignment with the port 53, so that the stream of vapor from the latter is injected into the port 58 and draws in air with it. A short tube 60 is adjustably threaded within the flange 60 and serves to 130

regulate the amount of air drawn into the mixing passage 57. In the construction shown, an eye 61 is formed at the top of the U-shaped portion 57 by which to hang the lamp, if desired. The ends of the U-shaped passage 57 extend through the disk 56 forming two outlets for the gas, which in the form shown in Figs. 1 and 3, open into a cup shaped chamber 62. In the form shown the upper end of this chamber is threaded into a depending annular flange 63 on the disk 56. A laterally projecting deflector plate 64 is centrally mounted in the upper end of the chamber 62 and is gripped between a flange 65 thereon and the flange 63. This chamber or burner head 62 surrounds the pipe 34 and its lower contracted end is provided with a burner and is adapted to engage the upper end of a mantle. The burner comprises a perforated disk 66 having a central opening through which the tube 34 extends and which is held in place by a flanged collar 67 secured upon the lower end of the burner head. The collar 67 performs the additional function of retaining the upper end of a mantle 68 indicated by the dotted lines in Fig. 3 and in full lines in Fig. 1, which is gathered and tied above said collar. The mantle is a sleeve, open at both ends, and extends around the tube 34. Its lower end is gathered and tied within the groove of a collar 69 mounted on the tube or pipe 34. The collar 69 is adjustably held in place by a set screw 70.

On the pipe 34 below the collar 69 is rigidly secured a generating cup 71. This cup surrounds the pipe 34 and is filled with asbestos 72. In the construction shown, the projecting arms 73 of a shade-holder are fixed to the cup 71. These arms carry a ring 74 that supports a shade 75. Preferably, also the ends of the deflector plate 64 are curved (see Fig. 2) to engage the upper contracted rim of the shade, so that this plate also serves as a shade support.

The mantle 68 may be readily placed in position, by unscrewing the disk 56 from the tip 51, and removing it and the parts 57 and 62 which are secured thereto. When it is desired to use a double burner, the burner head or chamber 62 and mantle 68 are removed and two tubes 76, carrying burners 77 and bag mantles 78, are screwed into the internally threaded lower ends of the U-shaped mixing passage 57, as shown in Fig. 2a.

The operation of the lamp is as follows: First, the cap 10 is removed and gasoline or kerosene, is poured into the tank through the filler pipes 9 and 5 until its level reaches the lower end of the pipe 5, at which point the liquid will back up into said pipes and no more can be poured in. The cap 10 is then replaced and the nipple 16 is unscrewed

until its shoulder 20 raises the disk 19 and valve 15. A small pump, such as is used for bicycles, is then pressed against the end of the nipple 16 and air is forced into the tank until sufficient pressure is attained. The compressed air in the tank will force the liquid fuel up through the supply pipe 23, and into the generator tube or pipe 34, when the controlling valve 26 is opened. The nipple 16 is then screwed tightly to place so that the valve 15 closes the port 13 and prevents the escape of air or liquid fuel. The asbestos 72 in the generating cup 71 is saturated with alcohol and the latter is ignited to heat the generating tube 34. The diameter of the filler rod 47 is slightly smaller (preferably about three hundredths of an inch) than the bore of the tube 34, so that the liquid passes between the wall of the tube and the rod in a thin film and is readily vaporized when the tube is heated. The fuel is thus forced out in a fine spray or vapor through the small port 53 and up through the inlet port 58 into the passage 57. As the fine stream of vaporized fuel passes into the port, air is drawn in and is thoroughly mixed with it in the U-shaped passage 57 and in the chamber 62. The gas mixture passing from the lower end of the chamber or burner head 62 is ignited and burns in the usual manner to heat the mantle 68 to incandescence. The supply of liquid fuel is readily regulated by turning the needle valve 26 through the medium of the knob 31. The air supplied to the mixing passage can be regulated to the proper amount by adjusting the short pipe or nipple 60.

If the discharge port 53 is clogged in the improved construction, the fine pin or wire 50 is always in readiness to clean the port, even when the lamp is burning. This is effected by turning the crank 41 and shaft 37 to reciprocate the connected rods 45 and 47 to force the pin 50 through the port. The connection between the rods 45 and 47 can be adjusted to properly position the tip cleaning pin or wire 50 relatively to the port 53. The burner that heats the mantle and which, in the preferred form, extends around the generating tube 34, also supplies all the heat necessary to vaporize the liquid fuel, and no other burner is required for this purpose after the lamp is started. The generator cup 71 is, of course, only used to give the lamp its initial start.

The deflector plate 64 is arranged below and at right angles to the U-shaped mixing passage or pipe 57 and projects laterally in line with an opening between the sections of mixing pipe, as shown in Fig. 2. It thus deflects the combustion products rising from the burner and prevents them from entering the mixing passage through the inlet port 58 thereof.

As already described, when it is desired to use two burners the burner head or chamber 62 and the mantle 68 are removed and two separate burners are inserted in the lower, threaded end portions of the U-shaped passage 57. These two burners are placed close to the tube 34 and serve to heat the same. As stated the arrangement of the mantle about the generating tube is preferred, particularly if kerosene is the liquid fuel used.

While the drawings illustrate the present improvement as embodied in a portable vapor lamp, many features may be employed in other types. Obviously, also, changes may be made in the details set forth without departure from the essentials of the invention as defined in the claims.

I claim as my invention:—

1. In a portable vapor lamp, the combination of a fuel tank forming the lamp base, an upwardly extending generator pipe, a burner support thereon, a coupling member at the lower end of said generator pipe having a threaded connection through the upward central portion of said tank, and an outer finishing shell for said tank, clamped in position between the same and said coupling member.

2. In a vapor lamp, the combination with a generator pipe and burner, of a fuel tank, a valve casing interposed between said tank and said generator pipe and having an enlarged bore communicating with said tank and a contracted fuel supply port communicating with said generator pipe, a fuel supply pipe extending upwardly from the lower portion of said tank through the enlarged bore of said valve casing and communicating with the contracted port thereof, and a valve-controlled filler tube mounted on said valve casing and communicating with the enlarged bore thereof.

3. In a vapor light apparatus, the combination of a straight, vertical generator pipe having a discharge orifice at its upper end, an inverted mixing chamber and burner mounted upon the upper end of said generator pipe, a valve casing to which the lower end of said generator pipe is connected, a fuel supply pipe connected to said valve casing, a valve having a stem projecting laterally through said valve casing for controlling communication between said fuel supply pipe and said generator pipe, a rod within said generator pipe having a tip cleaning device for said orifice at its upper end, the lower end of said rod extending within and terminating in the upper end of said valve casing above said valve and a stem extending laterally through said valve casing above said valve and operatively connected to said rod, substantially as described.

4. In a vapor lamp, the combination of

a fuel supply tank forming the lamp base, a valve casing mounted on said tank, a fuel supply pipe connected to said valve casing and extending downwardly into said tank, a straight vertical generator pipe mounted on said valve casing and having a contracted discharge port at its upper end, an inverted mixing chamber and burner mounted on the upper end of said generator pipe and arranged to heat the same, a longitudinally movable rod arranged within said straight generator pipe and having means at its upper end for clearing and controlling said discharge port, the lower end of said rod being arranged and terminating within the upper portion of said valve casing, a valve having a stem extending laterally through said casing for controlling communication between said fuel supply pipe and said generator pipe, and a stem extending laterally through the wall of said casing above said valve and operatively connected at its inner end to the lower end of said rod, substantially as described.

5. In a vapor lighting apparatus, the combination of a vertical generator pipe having a discharge port at its upper end, and an inverted U-shaped mixing chamber mounted upon the upper end of said generator pipe and having at its central portion an inlet port arranged above and in line with said discharge port, said mixing chamber having means at its lower ends for interchangeably supporting a single annular head about said generator pipe, or two burner heads arranged on opposite sides of the generator pipe and communicating respectively with the depending portions of said U-shaped mixing chamber.

6. In a vapor lighting apparatus, a vertical generator pipe having a discharge port at its upper end, an inverted, U-shaped mixing chamber mounted upon the upper end of said generator pipe and having, at its upper central portion, an inlet port arranged above and in line with said discharge port, and a burner head secured at its upper end to the lower portion of said mixing chamber and encircling said generator pipe.

7. In a vapor lighting apparatus, a vertical generator pipe having a discharge port in its upper end, a downwardly extending mixing chamber having an inlet port, above and in line with said discharge port, a burner head communicating with said mixing chamber and extending downwardly therefrom, and a deflector plate having portions projecting laterally from the lower portion of said mixing chamber, the ends of said deflector plate being adapted to serve as shade supports, substantially as described.

8. In a vapor lamp, the combination of a generator pipe, a tip therefor having a recess in its outer end, and a composition tip

piece molded in place within said recess and having a fine discharge port formed in the molding operation.

9. In a vapor lamp, the combination of a generator tube, a tip therefor having a bore terminating in a conical end, and said tip having an undercut recess in its outer end, a composition tip piece molded in place in said recess, and a reciprocating rod in said

generator tube having a tip cleaning needle 10 adapted to be inserted through said composition tip piece in the molding operation to form a fine discharge port therein.
